US00D876023S

(12) **United States Design Patent** (10) **Patent No.:** **US D876,023 S**
Eom (45) **Date of Patent:** **** Feb. 18, 2020**

(54) **AUTOMATIC PET FEEDER**

(71) Applicant: **SaltNLight Inc.**, Daejeon (KR)

(72) Inventor: **Bo Yun Eom**, Daejeon (KR)

(73) Assignee: **SaltNLight Inc.**, Daejeon (KR)

(**) Term: **15 Years**

(21) Appl. No.: **29/674,854**

(22) Filed: **Dec. 26, 2018**

(30) **Foreign Application Priority Data**

Jun. 28, 2018 (KR) 30-2018-0029860

(57) **CLAIM**

The ornamental design for an automatic pet feeder, as shown and described.

DESCRIPTION

FIG. 1 is a front perspective view of an automatic pet feeder showing my new design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is a bottom perspective view thereof; and,
FIG. 9 is a reference view showing use state thereof.

(Continued)

The broken lines are for illustrative purposes only and form no part of the claimed design.

1 Claim, 9 Drawing Sheets
